UNITED STATES PATENT OFFICE.

THOMAS W. PEDERSEN, OF NEW YORK, N. Y., ASSIGNOR TO OIL JACK, INC., OF NEW YORK, N. Y., A CORPORATION OF NEW YORK.

FLUID-ACTUATED JACK.

Application filed June 1, 1925. Serial No. 34,100.

This invention relates to fluid actuated jacks, and more particularly to that type of jack which includes a self-contained reservoir for the actuating fluid, together with a pressure means for transferring the actuating fluid from the reservoir to the jack cylinder in which the stem operates.

The principal object of the present invention is to provide a compact and easily manufactured jack of this general type in which the number of parts is reduced to a minimum.

Another object of the invention is to provide a jack in which the main cylinder, pump cylinder and reservoir are integrally formed.

A still further object of the invention is to provide novel and advantageous means of guiding the stem in the cylinder and for preventing leakage where the stem projects from the cylinder.

The invention further resides in certain novel features and details of construction as hereinafter fully described and as illustrated in the attached drawings, in which:

Figure 1 is a side elevation of a jack made in accordance with my invention;

Fig. 2 is a vertical section on the line 2—2, Fig. 3;

Fig. 3 is a sectional elevation on the line 3—3, Fig. 1; and

Fig. 4 is a transverse section on the line 4—4, Fig. 1.

With reference to the drawings, the jack comprises an integral casting 1 including a central main cylinder 2 in which the stem 3 of the jack operates in well known manner. The lower portion of the casting is enlarged and is made hollow to provide a reservoir chamber 4 for an actuating fluid, and this chamber communicates through a channel 5 and port 6 with the bottom of a pump cylinder 7 formed in an integral boss 8 of the casting, as clearly illustrated in Fig. 3. The pump cylinder 7 connects through a port 9 and passage 10 with the bottom of the main cylinder 3, and valves 11 and 12 control the passage of the fluid from the reservoir chamber to the pump cylinder, and from the pump cylinder to the main cylinder 3, as will hereinafter be more fully described.

It will be noted that the channel 5 may be formed by drilling from the outside of the casting 1 into the bottom of the reservoir chamber 4; that the port 6 may be formed by drilling through the bottom of the pump cylinder 7 into the said channel 5; and that the

channel 10 may also be formed by drilling from the outside of the casting through a web 13, provided for the purpose, into the bottom of the main cylinder 2. It will further be noted that the channel 10 passes through a transverse chamber or recess 14, at the inner end of which the port 9 is formed. The outer end of the channel 5 is closed in the present instance by a plug 15, while the outer end of the channel 10 is closed by means of a screw plug 16, the channel being sealed by a suitable gasket 17 in the bottom of the counterbore provided for the head of said screw plug. The valve 11 consists of a ball resting by gravity in the bottom of the pump cylinder 7 and normally closing the port 6, while the valve 12 consists also of a ball normally retained to its seat, closing the port 9, as shown in Fig. 4, through the medium of a spring 18 in the chamber 14, the spring being confined between the valve 12 and the inner end of a tapered plug 19 threaded into the outer end of the chamber.

The reservoir chamber 4 has further communication with the main cylinder 2 through a passage 20 which enters the said cylinder at a point somewhat above the bottom, and the outer end of this passage 20 is normally closed by a manually actuatable valve 21 threaded into a plug 22 which in turn is threaded into a port in the outer wall of the chamber 4. The plug 22 includes a chamber for reception of suitable packing 23, and a follower ring 24 is threaded into the outer end of this chamber and retains the packing in place. The valve 21, as clearly shown in Fig. 2, projects beyond the outer end of the follower 24 and is provided with suitable projections 25 whereby it may be manually turned to close or open the passage 20, as may be desired.

The stem 3 which normally rests upon the head of a plug 26 inserted in an opening 27 in the bottom of the main cylinder 2, as clearly shown in Figs. 2 and 3, has an enlarged bottom portion 28, and threaded into a counterbored recess in the outer end of said main cylinder 2 is a collar 29 which slidably fits the stem 3 and acts with the enlarged portion 28 to guide the stem in the cylinder. This collar also cooperates with the enlarged portion 28 to prevent the stem from passing from the cylinder when in the extended position, the enlargement 28 engaging the under side of the said collar and retaining it in the cylinder. A slot or slots 28a is provided in the en-

largement to permit free passage of fluid between the opposite sides thereof.

Outwardly of the collar 29 the main cylinder 2 is provided with an enlarged counterbored recess 30 for reception of suitable packing elements 31, and these elements are retained in place by means of a follower ring 32 threaded into a third counterbored recess 33 at the extreme top of the cylinder, the following lower ring 32 functioning also to guide the stem 3 in the cylinder. As is customary, the upper end of the stem 3 has a reduced threaded portion for reception of a load-engaging head 34.

Operating in the pump cylinder 7 is a plunger 35 having attached to the bottom or inner end thereof suitable packing elements 36, by means in the present instance of a screw 37, the plunger 35 having pivotally secured to the upper end thereof, which projects out of the cylinder, a link 38, which link also pivotally connects with a lever 39 which is pivotally secured at 40 to the casting 1. This link 39 also has at the top a socket portion 41 for reception of a handle lever, not shown, whereby the lever 39 may be oscillated around its pivot to thereby reciprocate the plunger 35 in the cylinder 7. The top of the cylinder boss 8 is provided with a counterbored recess 42 for reception of suitable packing material 43, and a follower ring 44 is threaded into the top of the recess to retain the packing in place.

The casting 1 further comprises an integral handle portion 45, by means of which the casting may be easily gripped and held in position during the operation of the lever 41, the handle extending from the casting 1 in a direction substantially parallel to the direction which the handle lever assumes when inserted in the socket portion 41 of the lever 39 and to the plane in which the lever operates.

A port 46 extending from the outside of the casting into the chamber 4 from the top of the enlarged portion which encloses said chamber provides for the admission of the actuating fluid to the reservoir chamber, and this passage 46 is normally closed by a tapered plug 47 threaded into the outer end of the passage.

Operation of the jack will be readily understood by those acquainted with the art. With the parts as shown in Figs. 2 and 3, reciprocation of the pump plunger 35 in the manner indicated results in a withdrawal of the actuating fluid from the chamber 4 into the pump cylinder and a consequent discharge from the pump cylinder into the main cylinder 2 below the stem 3. Transference of the liquid in this manner results in an elevation of the stem 3 to the desired extent. When it is desired to lower the jack, the valve stem 21 is turned to open the port 20, which thereby permits the actuating fluid to flow back into the reservoir.

To prevent undue outward movement of the plunger 35 with respect to the pump cylinder 7, I provide a laterally extending lug 50 on the lever 39 which is adapted to engage a similar lug 51 extending from the main casting 1 of the jack, when the plunger 35 has attained its practical limit of outward movement.

The herein described construction provides a jack that is easily manufactured at comparatively low cost, involves a minimum number of parts, and is extremely efficient in operation, and durable. The jack also possesses great strength and rigidity due in part to the multiple means of guiding the stem in the cylinder.

It will be apparent that there may be some modification without departure from the essential features of the invention.

I claim:

1. A fluid operated jack comprising an integrally formed reservoir, base, main cylinder and pump cylinder; a movable stem in said main cylinder having an enlarged portion in the cylindrical surface of which are formed slots to permit free passage of fluid from one side thereof to the other; a threaded collar screwed into a recess in the outer end of the main cylinder and slidably fitting said stem thereby acting jointly as a guide therefor and as a stop for limiting its travel by engagement with said enlarged portion; a plunger in the pump cylinder; and means for controlling the flow of fluid from the main cylinder to the reservoir.

2. A fluid operated jack comprising an integrally formed reservoir, base, main cylinder and pump cylinder; a movable stem in the main cylinder having a diameter smaller than the bore of said cylinder; an enlarged portion formed on the end of said stem slidably fitting the bore of the cylinder and having in the cylindrical surface thereof slots permitting free passage of fluid from one side thereof to the other; a threaded collar screwed into a recess near the outer end of the main cylinder forming a guide for said stem and a stop to limit its travel by engagement with its enlarged end; packing washers in a second recess adjacent said collar; a follower ring screwed into a third recess adjacent the second to retain the packing washers and to form an additional guide for the stem; a plunger in the pump cylinder; and means for controlling the flow of fluid from the main cylinder to the reservoir.

3. A fluid operated jack comprising a reservoir, main cylinder, and pump cylinder; a movable stem in the main cylinder having a diameter smaller than the bore of said cylinder; an enlarged portion formed on the end of said stem slidably fitting the bore of the cylinder; passages formed in said enlarged portion to permit free flow of fluid from one side thereof to the other; a collar detachably

mounted near the outer end of the main cylinder forming a guide for said stem and a stop to limit its travel by engagement with its enlarged end; packing means adjacent said collar; and means for providing and controlling a flow of fluid from the pump cylinder to the main cylinder and from the main cylinder to the reservoir.

4. In a fluid operated jack, the combination 10 of a cylinder; a movable stem in said cylinder of smaller diameter than the bore of the cylinder; an enlarged portion on the end of said stem slidably fitting the bore of the cylin-

der; passages formed in said enlarged portion to permit free flow of fluid from one 15 side thereof to the other; a guide ring slidably fitting the smaller portion of said stem and detachably mounted near the outer end of said cylinder; means for packing the outer end of the cylinder; a pump adapted to 20 supply fluid to said cylinder; a reservoir; passages connecting the reservoir with the pump and cylinder; and means for controlling the flow of fluid in said passages.

THOMAS W. PEDERSEN.
